EXERCISING DEVICE

Robert M. Rink, Goshen, Ind., assignor to The Goshen Manufacturing Company, Goshen,
Ind.

Application May 29, 1953, Serial No. 25,243

Term of patent 14 years

(Cl. D34—5)

To all whom it may concern:

Be it known that I, Robert M. Rink, a citizen of the United States, residing at Goshen, in the county of Elkhart and State of Indiana, have invented a new, original, and ornamental Design for Exercising Device, of which the following is a specification, reference being had to the accompanying drawing, forming part thereof.

The figure is a perspective view of an exercising device, showing my new design.

I claim:

The ornamental design for an exercising device, as shown.
